UNITED STATES PATENT OFFICE

HARVEY B. TROTT, OF MCKEESPORT, PENNSYLVANIA

WINDOW SCREEN

Application filed August 30, 1928. Serial No. 302,927.

My invention relates to window screens with metallic frames.

One object of this invention is to provide a window screen with an elastic frame which 5 grips the edges of the wire fabric and stretches it tight. Another object is to provide means whereby the screens may be connected by hinge-joints to window frames. Another object is to stiffen the screen frames 10 in their transverse directions and also to stiffen them against movements in the planes in which they may be. Another object is to provide a frame composed of a single piece. Other objects appear hereinafter.

15 Referring to the accompanying drawing, Fig. 1 is a side view of my improved screen; Fig. 2 an edge view of the same; Fig. 3 an enlarged side view of one corner of the screen; Fig. 4 a view of Fig. 3 viewed from 20 the right; Fig. 5, a side view of a screen before the frame is brought into final shape and clamped to the wire fabric; Fig. 6, a view of a blank from which one section of my screen frame is made, parts being broken 25 away; Fig. 7, a view of a short portion of the blank after it has been doubled on its longitudinal center; and Fig. 8, a section on the line 8—8 on Fig. 1.

In Figs. 1 and 2 I show a screen made of 30 duplicate adjustable rectangular sections or members 10 and 11. As they are alike only one member will be described.

The frame for each member is made from a single rectangular sheet-metal strip or 35 blank doubled along its longitudinal central portion and bent at three places at right angles to form three corners of the frame, the ends of the blank meeting and forming the fourth angle of the frame which is rectangular.

The blank shown in Fig. 6 has, where each of three corners are to be made, a triangular opening 12 with its inner angle 13 (which is a right angle) pointing toward the longitudinal 45 center of the blank. The side 14 of each opening lies parallel with the longitudinal edges 15 and 16 of the blank. A slit 17 is made from the side 15 of the blank to the center of the side 14 of each opening 12. The slits 17 are at right angles to the side 15,

The blank has at the left of the side 14 of each opening 12 a slit 18 which is an extension of the said side 14 and lies parallel with the side 15 of the blank. A slit 19 extends from the side 16 of the blank toward the angle 13 of each opening 12 and is at right angles to the side 16. The slits on opposite sides of each opening 12 are linearly arranged. The inner ends of the slits 19 do not reach the angles 13, but leave a space or portion 20 which is to form the corners of the frame. The spaces 20 equal the thickness of the frame. The ends of the blank have notches 21 and 22 which are each half the size of an opening 12.

If the blank is made into a hoop with its 55 ends contiguous and matched, the notches 21 and 22 would together form an opening having exactly the same size, shape and arrangement in the blank as the openings 12 have. The notch 22 has the slit 18^a which corresponds to the slit 18 accompanying each opening 12.

Assume that the blank shown in Fig. 6 is to form the frame for the screen section 11, having the sides 23, 24, 25 and 26. The section 23^a of the blank between the right hand end and the nearest opening 12 is to form the frame side 23; the section 24^a between the latter opening 12 and the next one to the left is to form the frame side 24; the section 25^a between the latter opening and the next opening 12 to the left is to form the frame side 25; and the section 26^a between the latter opening and the left-hand end of the blank is to form the frame side 26.

There are a number of pairs of parallel slits extending from the side 16 of the blank about to the center of the blank. The blank section 23^a has two pairs of slits near each end forming the tongues 27. The blank section 24^a has near the right hand end a pair of slits forming the narrow tongue 28 and near the other end a pair of slits forming the tongue 29. The blank section 26^a has near its right hand end a pair of slits forming the tongue 30 and near its left hand end a pair of slits forming the narrow tongue 31.

The blank is folded upon itself along its central longitudinal portion so as to bring the upper part over the lower part, with the

sides or edges 15 and 16 lying in the same plane. The opposing or inner faces of the folded blank are spaced apart to receive between them the edges of the wire fabric 32.

5 The longitudinal strip of the blank lying between the line 33 connecting the inner ends of the slits 19, and the line 34 connecting the angles 13 and the inner ends of the notches 21 and 22 will form the periphery of the frame 11 when the sections of the folded blank are formed into a rectangle. The folded blank has the side containing the openings 12 and the notches 21 and 22 provided with a bead 35, the slits 18 and 18^a coming at the inner edge of the bead.

10 15 The blank doubled as shown in Fig. 7 is bent at the places or portions 20 to form a rectangular figure or frame; the two sides about the angle 13 of each opening 20 come together to form mitre joints 36, while the corresponding sides of the notches 21 and 22 come together to form the mitre joints 36^a. While the corners of the frame are being made, the tongues 37 at the right of each slit 25 17 are passed through the slits 18 and beneath the bead 35, as clearly shown in Fig. 3. The tongue 37 at the left hand end of the blank passes through the slit 18^a.

20 25 The rectangular wire fabric 32 has its edges 30 between the opposed folded members of each side of the frame. It will be noted that the sides of the frame have the intermediate portion bowed outwardly initially as shown in Fig. 5. The sides of the frame are afterwards bent inwardly so as to form a rectangular figure, at which time the portions of the frame lying at opposite sides of the fabric 32 are pressed tightly against the fabric. The pressure must be sufficient to securely hold the fabric between the folded members of the frame. The tendency of the frame sides to resume their bowed condition keeps the fabric tightly stretched in every direction.

30 35 The tongues 27 are swung out at right angles to the screen, their free ends being formed into eyes 38 to receive hinge-pins. The tongues 27 may also have a hole 39 (only one shown, Fig. 4) to receive a nail or screw. The tongues 27 for the section 11 are bent so as to project on the opposite side of the section from that from which it originated, as shown in Fig. 4. The tongues 27 for the section 10 project from the same side of the screen as that from which it originates, as shown at the left hand end of Fig. 1.

40 45 The tongues 29 and 30 are bent out of their original planes and formed into hook-like guides or members 40. The screen sections 10 and 11 lie one on the other and the hook-like guides 40 on one member hook over the edges of the other member and hold the members together and guide them as they slide on each other. This feature is shown in Patent No. 1,171,184 granted to J. A. Feierabend, Feb. 65 1916, and need not be further de-

scribed. This patent also shows and describes the manner by which applicant's fabric 32 is clamped in his frame sides.

The tongues 28 and 31 are bent out of their original planes to form stops 41. The stops 70 41 on one frame section engage the ends of the other frame section and prevent the accidental separation of the sections by their longitudinal collapsing movements.

I do not desire to be restricted to the precise structure shown and described as changes may be made within the scope of the invention as defined in the appended claims.

I claim:

1. In a window screen, two rectangular frames slidably connected together, and wire fabric secured to the frames and tongues integral with the opposite ends of the screens, the free ends of the tongues formed into hinge members.

2. In a window screen, two rectangular frames slidably connected together, and wire fabric secured to the frames and tongues integral with the opposite ends of the screens, 90 the free ends of the tongues formed into hinge members, and the tongues having openings for a fastening means.

3. In a window screen, two rectangular frames slidably connected together, wire fabric secured to the frames, and a tongue integral with the side of one frame and standing in the path of the other frame when the frames are collapsed to a predetermined degree.

4. A rectangular frame for a window screen comprising a strip of sheet metal folded lengthwise upon itself and lying in only two planes, providing two oppositely disposed spaced-apart walls, and a wire fabric having its edges secured between and by the said walls, the said walls being cut transversely at the corners of the frame and the folded edge being continuous and bent at the corners to form right angle corners and the walls adjacent to the cuts overlapping each other at the corners to form four thicknesses.

5. A rectangular frame for a window screen comprising a strip of sheet metal folded lengthwise upon itself and lying in only two planes, providing two oppositely disposed spaced-apart walls, and a wire fabric having its edges secured between and by the said walls, the said walls being cut transversely at the corners of the frame and the folded edge being continuous and bent at the corners to form right angle corners and the walls adjacent to the cuts overlapping each other at the corners to form four thicknesses and the walls having lateral beads forming miter joints at the corners of the frame.

6. A rectangular frame for a window screen comprising a strip of sheet metal folded lengthwise upon itself and lying in only two planes, providing two oppositely dis-

posed separated-apart walls, and a wire fabric having its edges secured between and by the said walls, the said walls being cut transversely at the corners of the frame and the folded edge being continuous and bent at
5 the corners to form right angle corners and the walls adjacent to the cuts overlapping each other at the corners to form four thicknesses, and the sides of the frame being under elastic tension tending to move the fabric
10 outwardly in the plane thereof.

In testimony whereof I affix my signature.
HARVEY B. TROTT.
